DESIGN FOR A WALL CLOCK

William E. Bentzinger, Sioux Falls, S. Dak., assignor to General Time Instruments Corporation, New York, N. Y., a corporation of Delaware

Application January 30, 1946, Serial No. 126,090

Term of patent 14 years

(Cl. D42—7)

To all whom it may concern:

Be it known that I, William E. Bentzinger, a citizen of the United States, residing at Sioux Falls, in the county of Minnehaha and State of South Dakota, have invented a new, original, and ornamental Design for a Wall Clock, of which the following is a specification, reference being had to the accompanying drawing, forming a part thereof.

Figure 1 is a perspective view showing a wall clock embodying my new design.

Fig. 2 is a side elevational view of the clock.

Fig. 3 is an exploded view in side elevation showing the crystal separated from the clock.

Distinguishing features of this design include a convex dial, curved hands, and a convex crystal having a cylindrical portion which is joined to the clock case.

I claim:

The ornamental design for a wall clock, substantially as shown.

WILLIAM E. BENTZINGER.
